UNITED STATES PATENT OFFICE.

ALBERT F. TANNER, OF GREENFIELD, WISCONSIN, ASSIGNOR TO IDEAL CONTINUOUS CYANIDING PROCESS COMPANY, OF DAVENPORT, IOWA, A CORPORATION OF IOWA.

CYANIDING-TOWER.

1,201,386.

Specification of Letters Patent. Patented Oct. 17, 1916.

Application filed July 14, 1915. Serial No. 39,735.

To all whom it may concern:

Be it known that I, ALBERT F. TANNER, a citizen of the United States, and resident of the town of Greenfield, in the county of Milwaukee and State of Wisconsin, have invented new and useful Improvements in Cyaniding-Towers, of which the following is a description, reference being had to the accompanying drawings, which are a part 10 of this specification.

This invention has for its object to provide means for agitating, aerating and heating ore pulp and cyanid solution to enable the latter to thoroughly dissolve all gold 15 and silver values from the ore pulp in a continuous process cyaniding system.

Another object of the invention is to provide such a cyaniding means in which the ore pulp is treated in small quantities and 20 is gradually advanced upwardly through a series of steps, the elevating means being so designed as to select the lighter particles in transferring material from one step to another, thus having the tendency to leave 25 the heavier particles containing values to prolong the treatment thereof.

Another object of the invention is to provide such a cyaniding tower of a multiple unit construction permitting expansion and 30 contraction thereof to fit the requirements of a particular ore at a particular time, and to be varied with the variation of such requirements from time to time so as to increase or reduce the extent of the cyaniding 35 treatment in a continuous process.

Another object of the invention is to permit of adjustment of the elevating means with respect to the pans containing the material so as to vary the selective ability of 40 such elevating means and allow of a greater or less space for the escape of the heavier particles of value bearing ore from the action of the elevating means.

Another object of the invention is to provide suitable means for supporting and adjusting the position of the heating pipes and 45 the pans.

Another object of the invention is to provide a common means for driving the elevating means of the several pans and for maintaining proper driving connection therewith.

Another object of the invention is to perfect details of construction in a cyaniding tower of this type.

With the above and other objects in view the invention consists in the cyaniding tower as herein claimed and all equivalents.

Referring to the accompanying drawings in which like characters of reference indicate the same parts in the different views: Figure 1 is a side elevation of a cyaniding tower constructed in accordance with this invention, parts being broken away for clearness; Fig. 2 is a sectional view showing the construction and arrangement of the lowermost pan thereof; Fig. 3 is an enlarged detail sectional view of a fragment of the tower; Fig. 4 is a similar view at right angles thereto; Fig. 5 is a similar view of the near supporting posts shown in Fig. 3 as viewed in the opposite direction; Fig. 6 is a detail view of one of the elevating and agitating cylinders; Fig. 7 is a detail view of the upper edge of one of the inclined pans; Fig. 8 is a view showing a modified form of tower frame with a different arrangement of heating pipes for supporting the inclined pans; and Fig. 9 is a diagram view showing the use of the auxiliary sectional elevating tower and the sectional descending tower.

In these drawings 10 indicates a frame, preferably made up of a pair of uprights on each side thereof and connected at the base and top by cross pieces to form a rectangular construction which is preferably, though not necessarily, made up of sections which are uniform except as to the top and base sections 101 and 102 respectively so that sections may be added or removed without altering the general construction of the machine, the front and rear parallel uprights being preferably spliced as shown to facilitate this expansion and contraction of the machine.

In describing the machine the near side, as shown in Fig. 1, will be referred to as the front, merely for convenience. Double brackets 11 are adjustably secured to the inner faces of the rear frame standards or uprights, as best seen at the upper part of Fig. 3, and have vertical slots through which the clamping bolts pass for this purpose. Each of these double brackets has four steps 105 or angular projections 13 forming pipe rests, the two on one side being one above the other, and the two on the other side being also one above the other, but one being higher and the other being lower than those 110

on the other side. Heating pipes 14 extend horizontally from near the front to near the rear of the machine and are clamped to the pipe rests 13 by means of U-shaped clips 15, the pipes on the two lower pipe rests being connected together, and the pipes on the two upper pipe rests being connected together at the rear of the machine, as shown in Fig. 3, while the pipes on the left pipe 10 rests are connected together at the front of the machine, and those on the right are connected with the pipes of the adjacent brackets above and below so that the entire heating pipe 14 forms a sinuous coil, the bends 15 of which are alternately positioned at the right and left sides of the machine, and steam or hot water is circulated through the coil to heat the sheet metal pans 16 which rest thereon. The front ends of the bends 20 of the heating pipe 14 are similarly supported by double brackets 17 adjustably secured to the uprights of the front of the frame by bolts 12 as before, the principal difference between the brackets 11 and 17 25 being that the latter are provided with only two pipe rests 13, instead of four. The pans 16 have inclined bottoms with front and rear upstanding walls and a curved upstanding wall extending with the adjoining front 30 and rear walls considerably higher than the remainder of the pan to fit approximately a quarter way around a cylindrical elevating and agitating means which is contained therein, as will be later described. The 35 upper end of the pan is without an upstanding wall and constitutes a trough with an adjustable lip 16' secured to its edge to receive the material from the elevating cylinder of the pan below. Flanges 18 on the 40 bottom of the upper end of the pan engage the pipe 14 and angular projections 19 on the sides of the pan are connected by bolts 20 with projections from the pipe rests 13.

Angular brackets 21 are adjustably secured to the sides of the frame and have adjustably mounted in their outstanding grooved portions bearing boxes 22 in which are journaled shafts 23. The agitating and elevating cylinders before referred to are 45 fixed on these shafts 23 and comprise end disks 24, which fit close against the side cheeks of the pan 16 and are approximately concentric with the curved portion of the bottom of the pan, and metal plates or blades 50 55 which fit between the disks 24 and have flanges at their ends by which they are riveted or otherwise secured to the disks. The said plates 25 are arranged tangentially to a circle of smaller diameter than the disks and are regularly positioned and extend from near the periphery of the disk to the point of contact with the adjacent plate, thus forming a cylinder or drum of V-shaped pockets. Each pocket is sealed 60 65 or has the space at the lowermost part there-

of plugged with a filling of cement 26 to prevent leakage from the pocket, to the interior of the cylinder, and a brace rod 27 extends across the pocket and is connected with the two plates 25 between which the 70 pocket is formed. The connecting bolt or rivet which fastens one brace rod 27 to the plate 25 connects the brace rod of the next pocket thereto also. At their outer edges the plates 25 have reversible wearing strips 75 28 bolted thereto and projecting beyond the plates to take the wear thereof and having their edges turned outwardly and when these strips become worn they may be reversed so as to present their other edges, and when 80 they are no longer useful they may be substituted by others.

Each shaft 23 is provided with a sprocket wheel 29 on its end, and a chain 30 which is driven from a sprocket wheel 31 on a suitably driven drive shaft 32 journaled on the top section of the frame passes up and down the frame and in so doing engages the sprocket wheels 29 of all of the shafts of the cylinders. The downwardly traveling 90 portion of the chain engages the sprocket wheels on the same side thereof as the upwardly traveling portion of the chain so that the cylinders on the two sides of the machine turn in opposite directions as is 95 necessitated by the reverse arrangement of the inclined pans and their cylinders, for each cylinder is to be turned so that the portion thereof coöperating with the curved walls of the pan moves upwardly with its 100 plates 25 projecting in the same general direction, that is, the plates traveling with their free edges in advance to scoop material from the bottom of the pan and lift it with the coöperation of the curved portion 105 of the pan until the pockets are so nearly upright that they are capable of retaining the material. Then, as the pockets travel over the cylinder and their front walls begin 110 to decline, the material runs down such declining walls into the trough-like open end of the pan above. An idle sprocket wheel 33 forms the turning point between the descending and the ascending portion of the chain. Bent slide rods 34 are adjustably 115 secured through elongated slots to the frame 10 and carry idle sprockets 35 which bear against the chain 30 and hold it in engagement with the sprocket wheels 29.

The lowermost pan 16 instead of having 120 its upper end directed toward the opposite side of the machine from the side on which its cylinder is mounted extends the other way so as to form a receiving trough into which the material is originally delivered to 125 the machine, such pan being supported by a bracket 36 and having a curved plate 37 mounted therein to coöperate with the cylinder in lifting the material therefrom and delivering it to the next pan. The upper- 130

most pan 16 discharges into an inclined trough 103, shown in dotted lines in Fig. 1, through which the material is conducted away from the tower. A platform 38 is supported on each side of the tower by angle iron beams 39 which are secured to the sides of the frame and are held in place by angle iron braces 40. These platforms enable inspection of and attention to the pans and their cylinders at the upper portion of the tower.

In operation power applied to the shaft 32 causes the chain to travel up and down the tower and turn all of the cylinders by its connection with their sprocket wheels. The finely crushed ore pulp and the cyanid solution which are delivered to the lowermost pan 16, usually from a stamping mill, are subjected to the action of the cylinder in said pan, particles being lifted a short distance thereby and then slipping back into the pan while a part thereof will continue with the cylinder until the pocket in which it is contained passes over the center of the cylinder. Then the material slides down the inclined front wall of the pocket and into the trough-like upper end of the next pan, down which it travels to the cylinder of such pan by reason of the inclined bottom of the pan. This operation is repeated for each of the numerous pans in the tower and the scouring of the particles of sand and ore by the action of the cylinders, which are preferably set a short distance away from the rounded portion of the pan, so that there is the desired slippage of material from the pockets back into the pan during the upward travel of the pockets, serves to keep the exposed surface free from the protecting film which is produced by the action of the cyanid solution or acids in the ore, thus enabling the cyanid solution to continue its action in dissolving the values. This scouring action effected by strong agitation at the bottom of each of the solution pans throughout the entire tower is of material assistance in accomplishing the complete dissolution of the values, as the operation not only serves to keep exposed ore surfaces clean, and therefore subject to the action of the solvent, but it serves to wear away the surfaces of particles and expose value bearing portions thereof which may have been concealed otherwise, and the very fact that a particle of ore containing value is naturally heavier results in its travel through the tower being retarded by its more frequent escape from the elevating action of the cylinders than a lighter particle of ore or sand not containing value. The escape of the heavier particles from the lifting action of the cylinder is more frequent because such particles as a class will naturally take the lowermost position in the pan and on being moved along by the rotating blades of the cylinder

will be first to slip out of the range of said blades to fall back to the bottom of the pan again, and are thus constantly kept in motion. Not only is the dissolution of the values facilitated by the agitating and scouring action above referred to, but the heating of the materials by the heating pipe 14 further accelerates the dissolution, and the aeration that takes place as the result of the turning of the cylinders to bring the air filled pockets beneath the surface of the liquid where the air escapes and is replaced by liquids and solids is of further benefit by supplying the oxygen necessary for the chemical action by which dissolution is accomplished.

The adjustment of the cylinders both as to vertical clearance and horizontal clearance is permitted by the sliding connections of the cylinder bearings 22 and their brackets 21, so that the desired amount of slippage of the heavier particles of ore from the elevating cylinders may be provided to suit the requirements of each particular case.

As stated, the tower need not be of a sectional frame construction, but this is not only a matter of convenience, as for transportation through mountainous country, but is actually of value in the operation, from the fact that it permits of exact adjustment of the size of the tower to suit the particular requirements of the ore at any particular time, allowing for expansion and contraction to adapt itself to the varying conditions of the mine from time to time. It is a well known fact that a mine does not run uniformly as to the solubility of its ore, and consequently there is necessity for a more prolonged cyaniding treatment at one time than at another, and this sectional construction of the elevating tower permits of the addition of tower units to prolong the cyaniding process when an examination of the tailings shows that values are escaping, and permits of the removal of sections as they become unnecessary with a more favorable run of the mine. Even though a single frame tower may be originally installed in a cyaniding plant with a capacity estimated as sufficient to properly dissolve all values, it may develop in course of time that additional cyaniding treatment is desirable, and then an auxiliary tower of sectional construction may be placed parallel with the main tower and enough sections added thereto until tests prove satisfactory, and a third tower containing the inclined pans 16 only, and without the heating pipes or the cylinders, of the same number of sections and consequently of about the same height as the auxiliary tower, may be positioned between the main tower and the auxiliary tower, or adjacent thereto, as shown in Fig. 9, so that the material after being elevated by the auxiliary tower may descend through the third tower from one

pan to the next, and thus receive an additional agitation and aeration without the expenditure of energy, the material being discharged from the third tower to the bottom 5 of the main tower.

In Fig. 8 is shown a modified form of the tower wherein the frame is composed of angle iron uprights 10' having long and short brackets 11' to support the coils of pipe 14 10 which are arranged in two series instead of one, and each series provides a length of pipe directly beneath the center of an agitating cylinder to form a rest for the lowest part 15 of the larger end of the pan 16, and its return length extending beneath the upper end of the next pan to form a rest therefor.

What I claim as new and desire to secure by Letters Patent is:

1. A cyanid plant, comprising a series of 20 inclined pans each arranged above the preceding pan in the series with its higher end above the lower end of the said preceding pan, and elevating means adjustably mounted at the lower end of each pan for lifting 25 material therefrom into the upper end of the succeeding pan in the series.

2. A cyanid plant, comprising a series of inclined pans arranged one above another with the lower end of each pan beneath the 30 higher end of the succeeding pan, and a pocketed cylinder adjustably mounted at the lower end of each pan and adapted to lift material therefrom to the upper end of the next pan of the series.

3. In a cyanid plant, a series of inclined pans arranged one above another with the lower end of each pan beneath the higher end of the succeeding pan in the series, the lower 40 end of each pan forming a concave, a pocketed cylinder rotatably mounted at the lower end of each pan and having the concave cooperate therewith for lifting material to the upper end of the next pan in the series, and means for varying the clearance space between the cylinders and the pans.

4. A cyanid plant, comprising a series of inclined pans with their lower ends curved to form concaves, a pocketed cylinder journaled across the lower end of each pan to cooperate with the concave portion of the pan to lift material therefrom to the upper end of the succeeding pan and means for varying the clearance space between the cylinders and the pans.

5. A cyanid plant, comprising a frame, a heating pipe extending back and forth across the frame alternately at the opposite ends thereof with its portions extending across the frame horizontal and its intermediate portions inclined, inclined pans removably resting upon the horizontal portions of the heating pipe, the lower end of one pan being beneath the higher end of the next pan in the series, adjustable brackets on the frame cylinders adjustably journaled in the brackets

across the lower ends of the pans, and blades on the cylinders for lifting material from the lower end of one pan to the upper end of the next pan.

6. A cyanid plant, comprising a frame, 70 pan supports extending across the frame, inclined pans resting on the pan supports with the lower end of one pan beneath the upper end of the next pan in the series, journal bearings adjustably mounted on the frame, 75 a shaft journaled in the bearings, a cylinder on the shaft, and blades on the cylinder for lifting material from the lower end of one pan to the upper end of the next pan.

7. In a cyanid plant, a series of inclined 80 pans arranged one above another with the lower end of each pan beneath the upper end of the next pan of the series, pocketed lifting drums rotatably mounted in the lower part of each pan and comprising end disks, 85 tangentially arranged plates secured to the end disks and forming pockets between them, clamping bolts at the edges of the plates, wearing strips secured to the edges of the plates by means of the clamping bolts, and brace rods connecting the clamping bolts of adjacent plates.

8. In a cyanid plant, a series of inclined 90 pans arranged one above another with the lower end of each pan beneath the upper end of the next pan of the series, and pocketed drums rotatably mounted across the lower ends of the pans comprising end disks, plates 95 connected to the end disks and arranged tangentially to form pockets between them, and reversible wearing strips secured to the edges of the plates.

9. A cyanid plant, comprising a frame, a series of inclined pans mounted thereon with the lower end of one pan beneath the upper 100 end of the next pan in the series, angle brackets vertically adjustable on the frame, bearings horizontally adjustable on the angle brackets, a shaft journaled in the bearings, and a pocketed drum mounted on the shaft 110 for lifting the material from the lower end of one pan to the upper end of the next pan of the series.

10. A cyanid plant, comprising a frame, a series of inclined pans arranged one above 115 another with the lower end of each pan beneath the upper end of the next pan of the series, pocketed drums journaled across the lower ends of the pans for lifting material therefrom to the upper ends of the succeeding 120 pans, sprocket wheels carried by said drums, and a suitably driven chain engaging the sprocket wheels on one side of the machine in its downward course and the sprocket wheels on the other side of the machine in 125 its upward course, slide rods adjustably mounted on the frame, and idle wheels carried thereby and engaging the chain for holding it in engagement with the sprocket wheels.

11. In a cyanid plant, a frame formed of interfitting similar sections, a series of inclined pans arranged one above another with the lower end of each pan beneath the upper 5 end of the next pan of the series and secured to the frame sections, pocketed drums journaled across the lower ends of the pans for lifting material therefrom to the upper ends of the succeeding pans, and a common 10 means for rotating the drums of the assembled frame sections.

12. A cyanid plant, comprising a frame, double brackets adjustably mounted thereon and provided with pipe seats at different 15 elevations, a sinuous heating pipe extending back and forth across the frame alternately at the opposite ends thereof and resting on the pipe seats with its portions extending across the frame horizontal and its intermediate portions inclined, inclined pans removably resting upon the horizontal portions of the heating pipe, the lower end of one pan being beneath the higher end of the 20 next pan in the series, and drums journaled in the frame across the lower end of the pans and provided with pockets to lift the material from the lower end of one pan to the upper end of the next pan.

13. In a cyanid plant, an elevating tower, 30 comprising a series of inclined pans arranged one above another with the lower end of each pan beneath the higher end of the

succeeding pan, and a pocketed cylinder mounted at the lower end of each pan and adapted to lift material therefrom to the upper end of the next pan of the series, an auxiliary sectional elevating tower comprising interfitting frame sections similarly provided with inclined pans and pocketed cylinders, and a sectional descending tower 40 formed of interfitting frame sections provided with inclined pans, one discharging into another, and receiving material from the upper end of the auxiliary tower and delivering it to the lower end of the first mentioned elevating tower.

14. A cyanid plant, comprising a series of inclined pans arranged one above another with the lower end of each pan beneath the higher end of the succeeding pan, a pocketed 50 cylinder mounted at the lower end of each pan and adapted to lift material therefrom to the upper end of the next pan in the series, and an adjustable lip secured to the upper edge of each pan to regulate the distance between said edge of the pan and the cylinder of the pan beneath.

In testimony whereof, I affix my signature, in presence of two witnesses.

ALBERT F. TANNER.
